(57) **CLAIM**

The ornamental design for an ankle support with elastic band as shown and described.

DESCRIPTION

FIG. 1 is a perspective view showing the new design for an ankle support with elastic band in a position of use;

FIG. 2 is a front view thereof;

FIG. 3 is a back view thereof;

FIG. 4 is a left view thereof;

FIG. 5 is a right view thereof;

FIG. 6 is a top view thereof; and,

FIG. 7 is a bottom view thereof.

The portions of the ankle support with elastic band in FIGS. 1-7 shown in broken lines are included to show features that form no part of the claimed invention. The dotted broken lines shown on claimed surfaces depict stitching and form a part of the claim.
